UNITED STATES PATENT OFFICE.

FRANCIS JACOB, OF WESTCOMBE PARK, ENGLAND, ASSIGNOR TO SIEMENS & HALSKE
A-G, OF BERLIN, GERMANY, A CORPORATION OF GERMANY.

SUBMARINE CABLE.

1,077,140.

Specification of Letters Patent. Patented Oct. 28, 1913.

Application filed April 30, 1912. Serial No. 624,263.

To all whom it may concern:

Be it known that I, FRANCIS JACOB, a British subject, residing at "Ellesdene," Westcombe Park, Kent, England, have invented certain new and useful Improvements in Submarine Cables, of which the following is a specification.

My invention relates to submarine cables having a self-inductive load distributed uniformly or at points.

During recent years great progress has been made in the development of telephony at great distances owing to the discovery of means which enable the self-induction of the lines used for conducting the telephonic alternating currents to be largely increased and the damping action of the capacity of the line to be thereby compensated. Both in bare lines and also in cables covered with paper and lead such as are used on land great success has been obtained by artificially loading the lines with self-induction. It is otherwise in the case of submarine cables when for mechanical and other reasons connected with the mode of laying them it is necessary to employ a solid, non-hygroscopic insulating material, *e. g.* guttapercha, closely surrounding the conductor. It has been found that in such cables the transmission of speech can be improved only to a very small

extent and on only relatively short lengths by artificially increasing their self-induction, so that for economic reasons the construction of marine cables with increased self-induction had to be desisted from in such cases.

A primary object of my invention is to remedy this defect. To this end, I employ a material for insulating the conductors which, it is true, has heretofore been used for insulating purposes but never in the combination proposed here and for the purposes in view in the present case, namely balata.

In order to explain my invention and its importance I shall first refer to the formulæ which determine the performance of telephone lines. These formulæ are developed by C. Baur in *Das elektrische Kabel*, 1910, pages 121 and 124, and by F. Breisig, *Theoretische Telegraphie*, 1910, pages 282 and 305, and *Elektrotechnische Zeitschrift*, 1908, page 588. They are also derived from the papers of Pupin, *Transaction American Institute, Electrical Engineers*, 1900, page 245, and *Electrical World*, 1901, page 587, 1902, page 384. For ordinary lines, *i. e.*, lines without artificially increased self-induction, the attenuation constant is calculated from the formula

$$I. \beta = \sqrt{\frac{1}{2} \sqrt{(A^2 + \omega^2 C^2)} (R^2 + \omega^2 L^2) - \frac{1}{2} (\omega^2 LC - AR)}$$

The value β which appears on the left hand side of the equation represents the attenuation constant of the conductor, which is developed from the Pupin formula for long conductors:

$$J_e = 2J_a e^{-\beta l}$$

for the end current J_e at the end of a conductor of length l (with a given starting current J_a). (See C. Baur *Das elektrische Kabel*, page 120.) From this formula it is apparent that the strength of the current at the end of a conductor with a given starting current becomes greater as β becomes smaller. Applied to telephone cables this means that the transmission of the telephonic communication becomes better as β becomes smaller or the smaller β is the greater can be the length of the cable with

equally good telephonic transmission. The letter ω means:

$$\omega = 2\pi n$$

in which n is the frequency or alternations per second of the alternating current transmitted on the conductor. The frequency of the telephonic communication currents amounts on an average to about: $n = 800$ per second, so that ω on an average is:

$$\omega = 2\pi n = 2 \times 3.14 \times 800 = 5,000,$$

in accordance with the international agreement of Paris. The value A in the equations means the so-called leakage conductance and is the same as the value a in the Pupin papers. It is measured in the units for conductivity as for example *Mho*. A is consequently equal to the conductance per

unit length (km) of a conductor of the leakage current circuit formed through the imperfect dielectric and is equal to the reciprocal value of the effective insulation resistance per unit length (km) of the conductor measured with alternating current, of the frequency here stated n equals 800 as an average. One obtains A in units of Mho if the alternating current insulation resistance measured in ohms is introduced into the computation. By inserting the numerical values of A , C , R and L such as are possessed by an ordinary guttapercha cable, for example, it will be readily understood that the leakage conductance A has hardly any influence at all on the value of β .

For lines having artificially increased self-induction the damping constants are calculated from the formula

20

$$\text{II. } \beta = \frac{R}{2} \sqrt{\frac{C}{L}} + \frac{A}{2} \sqrt{\frac{L}{C}}$$

wherein C and A have the same values as in the line without coils; R and L are the values increased by the additional resistance and the additional self-induction for unit length. All the values hold good as effective loop values for the unit length, *e. g.* per kilometer, and in general are referred to an average frequency, generally

$$n=800(\omega=2\pi n=5,000)$$

The first term of the right-hand side of Equation II for β contains the values of the resistance, capacity and self-induction; this term decreases as the self-induction increases and becomes smaller as the resistance of the loop is reduced. The second term contains the leakage conductance and also the capacity and self-induction; its value, however, becomes greater as the self-induction increases and increases, in addition, as the leakage conductance becomes greater. From this comparison of the two members of the equation it can be seen that when the self-inductive load is made great, the second member can be considerably greater than the first, particularly if the leakage conductance assumes a large value. If the leakage conductance be small, on the contrary, as *e. g.* in lead-paper cables, the leakage conductance member can be brought into a suitable relation to the resistance member, even if it is a matter of a thick conductor. By leakage conductance is understood, as is well-known, the reciprocal value of the effective alternating-current insulation for a given frequency, *e. g.*

$$n=800(\omega=2\pi n=5,000)$$

As the value of the leakage conductance depends, of course, on the thickness of the layer of insulation, thus on the capacity, it is necessary to state the value of the leakage conductance for a given capacity, preferably

unit capacity, thus the value A/C . This is preferable also because investigations heretofore made have shown that for a given material and frequency this magnitude remains approximately constant, is thus independent of the thickness of the layer of insulation and can therefore be looked upon as a kind of material constant. Now whereas modern paper-covered cables, such as are used for underground cables, have values of A/C which fluctuate between approximately 10 and 40, submarine cables having guttapercha insulation have a value of A/C fluctuating approximately about 100. This exceedingly high value of A/C is the cause of the above-mentioned economic failure when employing submarine cables having an artificial self-inductive load. It has been attempted to obviate this defect by making guttapercha cables in which the conductor was surrounded under the guttapercha covering with paper-air insulation. A usable form of this construction was also obtained. The construction had, however, the defect of small mechanical resistance which rendered its general employment difficult. I therefore attempted to discover a solid, non-hygrosopic material having leakage conductance values similar to those of the paper-air insulation which had proved satisfactory. Careful tests have shown that insulation having such properties is to be found in the material obtainable on the market under the name of balata and heretofore employed as an addition to or a substitute for guttapercha for insulating conductors. My investigations have shown that in pure balata the value of A/C fluctuates approximately about 10. As balata can be worked as easily as guttapercha and is not inferior to it in mechanical strength, it enables long submarine cables for the first time to be successfully loaded artificially with self-induction. A submarine cable constructed in this manner will have for A/C approximately the same values as an underground cable having paper-air insulation. Slight impurification of the balata or small admixtures of guttapercha would not affect this action of the balata when employed in submarine cables loaded with self-induction, in so far as the value of A/C is not considerably influenced. Its use for this purpose will not be practically affected, as long as the value A/C does not rise above 40. The same favorable action as in transmission between telephone stations will be obtained by means of balata when employed in the described manner in the transmission of telegraphic currents having a rapid succession of impulses.

One illustrative embodiment of my invention is represented by way of example in the accompanying drawings, in which—

Figure 1 shows in side view, with suc-

cessive layers broken away, and Fig. 2 shows in transverse section my improved cable.

Referring to the drawing, *a* designates the conductors and *b* the insulation composed of 5 balata surrounding the same.

c shows an iron wire armor and *d*, *d'* jute wrappings.

The enlargement X indicates the Pupin coil.

10 I claim:—

A submarine cable comprising in combination a plurality of conductors, an artificial

self-induction load thereon, and insulation composed of balata, closely surrounding each of said conductors for the purpose 15 specified.

In testimony whereof, I have signed my name to this specification in the presence of two witnesses.

FRANCIS JACOB.
